CLAIM

The ornamental design for a pair of bag hangers, as shown and described.

DESCRIPTION

FIG. 1 is a top and front perspective view of a pair of bag hangers showing my new design, the broken lines are for illustrative purposes only and form no part of the claimed design;

FIG. 2 is a left side elevational view of one of the bag hanger shown separately for convenience of illustration, the right side elevational view being a mirror image of that shown;

FIG. 3 is a front elevational view of FIG. 2;

FIG. 4 is a rear elevational view of FIG. 2;

FIG. 5 is a top plan view of FIG. 2; and

FIG. 6 is a bottom plan view of FIG. 2.
